A. Hall.

No Printed Specification Available

Straw Cutter.

Patented Nov. 7, 1835.

Ashman Wall of the Town of Hunt - New York
Letters Patent

The Schedule referred to in these Letters Patent and making part of the same containing a description of the words of the said Ashman Wall himself of his improvement in the machine for cutting straw

Be it known that A. Ashman Wall of the Town of Hunt, said State of New York have made an new and useful improvement in the machine for cutting straw, which is described as follows, reference being had to the annexed Drawing, making part of this specification:

The frame A and Box B of this machine will be made double to those in common use, my improvement consists in having a double knife C, placed angularly on the side of the sliding frame, in slot D, which is nearly the cutting box, and secured by screws, a strip of leather may be made of a single piece of black leather, so as to have its two cutting edges in an angular position in opposite directions, in order that the cutting shall be performed two and the centre of the box instead of the side, and that the operation of the knife shall have a tendency to press the substance to be cut into a more compact body whilst being cut. Also in having a gauge or regulator E, attached to the gate and regulated or gauged by screws, to determine the length of the straw to be cut. Likewise in having a strong spring F, secured by one end to the lower part of the frame, its other end connected to a lever G, by a small rod H, secured to the lever by an iron plate I, fastened on the top of the lever, to which lever the gate or sliding frame is attached by a pinman K, the spring being for the purpose of raising the gate and knives suddenly when a cut has been made. A Bradle L to be operated by foot is to be attached to the end of the lever. At the end of the cutting box near the knives is placed in an angular position a guard M, made of iron or wood and let in on the inside of the box.

The operator having placed the straw in his hands brings

at forward against the gauge with one hand whilst the other hand holds the top of the top of the gate one foot aside on the platform. The other hand on the end of the handle which drives down the lever gate and knives and the straw is cut. The foot is then raised and the spring raises the lever and gate and the straw is brought forward and another cut is made. and in this manner the operation is continued.

That I claim as my invention in the formation of the double knives arrangement of the gauge, and the mode of applying the spring as before described.
